[57] CLAIM

The ornamental design for a novelty telephone, substantially as shown and described.

DESCRIPTION

FIG. 1 is a top plan of my new design;

FIG. 2 is an end view;

FIG. 3 is a side view; and

FIG. 4 is a perspective view with the top turned back to reveal a telephone dial, and with the handset removed from the base.

FIG. 1

FIG. 2

FIG. 3
